(57) CLAIM

The ornamental design for a face mask with accessory loops, as shown and described.

DESCRIPTION

FIG. 1 is a top-front-left perspective view of a face mask with accessory loops showing my new design; FIG. 2 is a bottom-rear-right perspective view thereof; FIG. 3 is a front elevational view thereof; FIG. 4 is a detailed view of section 4 of FIG. 3; FIG. 5 is a rear elevational view thereof; FIG. 6 is a top plan view thereof; FIG. 7 is a bottom plan view thereof; FIG. 8 is a left-side elevational view thereof; FIG. 9 is a right-side elevational view thereof; and, FIG. 10 is a front elevation view thereof, wherein the face mask with accessory loops is being used and shown on a user. The dashed lines showing a human head and an ornamental chain are included for the purpose of illustrating environmental structure and forms no part of the claimed design.

1 Claim, 10 Drawing Sheets
